FIG. 1.

FIG. 2.

To all whom it may concern:

Be it known that I, Catherine W. Hull, a citizen of the United States, and a resident of Silver Spring, county of Montgomery, State of Maryland, have invented a new, original, and ornamental Design for a Textile Fabric, of which the following is a specification, reference being had to the accompanying drawing forming part thereof.

Referring to the drawing:

Fig. 1 is a plan view of a textile fabric, showing my new design. A design unit is outlined by dotted lines and is repeated as indicated over the fabric.

Fig. 2 is a plan view on an enlarged scale of the design unit.

I claim:

The ornamental design for a textile fabric, as shown and described.
